(57) **ABSTRACT**

A boat station (100), including: a seat base assembly (306) having a seat shelf (300), the seat base assembly configured to adjust a vertical position of the seat shelf; at least two seats (102); and an independent suspension assembly (104) for each seat. Each independent suspension assembly secures a respective seat to the seat shelf.

HELM STATION WITH ADJUSTABLE SEAT BASE

FIELD OF THE INVENTION

The invention relates to an adjustable seat for a helm station for a nautical vessel.

BACKGROUND OF THE INVENTION

A boat captain controls a boat in many diverse situations and may do so in a sitting position. Sea conditions can change the attitude of the boat. In addition, captains differ in height. Hence, seats with height adjustment are used. However, there is room for improvement.

BRIEF DESCRIPTION OF THE DRAWINGS

The invention is explained in the following description in view of the drawings that show:

FIG. 1 shows an example embodiment of a boat station with an example embodiment of a seat on an example embodiment of an independent suspension on an example embodiment of a seat base assembly that is in a lowered position.

FIG. 2 shows the boat station of FIG. 1 with the seat base assembly in an upper position.

FIG. 3 shows the seat base assembly of the boat station of FIG. 1 in the upper position.

FIG. 4 shows an example embodiment of the independent suspension of FIG. 1.

FIG. 5 shows an alternate example embodiment of a boat station with an alternate example embodiment of the seat on an alternate example embodiment of an independent suspension and an alternate example embodiment of the seat base assembly that is in the lowered position.

FIG. 6 shows the boat station of FIG. 5 with the seat base assembly in the upper position.

FIG. 7 shows an example embodiment of a seat and an example embodiment of an independent suspension with an example embodiment of a suspension component having an elastomeric element.

FIG. 8 shows a closeup of the independent suspension of FIG. 7.

FIG. 9 shows a rear perspective view of the independent suspension of FIG. 8.

FIG. 10A shows an example embodiment of the suspension components of FIG. 9.

FIG. 10B shows an alternate example embodiment of the elastomeric element of the suspension component.

FIG. 11 shows an example embodiment of a seat disposed on the independent suspension and the seat base assembly of FIG. 7 with the seat shelf in the lowered position.

FIG. 12 shows a closeup of the seat base assembly of FIG. 11 with the seat shelf in the lowered position.

FIG. 13 shows the independent suspension and the seat base assembly of FIG. 11 with the seat shelf in the upper position.

FIG. 14 shows a closeup of the seat base assembly of FIG. 13 with the seat shelf in the upper position.

FIG. 15 shows the seat, the independent suspension, and the seat base assembly of FIG. 7 disposed in an example embodiment of the seat base console.

FIG. 16 shows an example embodiment of a weather seal disposed between the seat base assembly and the seat base console of FIG. 11.

DETAILED DESCRIPTION OF THE INVENTION

The present inventor has created a unique and innovative boat station that provides a wide range of operating positions for a boat captain. Specifically, the boat station includes at least one independently suspended seat that is disposed atop a height-adjustable base. The at least one independently suspended seat optionally includes a separate height adjustment as part of the independent suspension. The independent suspension may also optionally include a unique and innovative elastomeric element.

FIGS. 1-4 show an example embodiment of the boat station and components thereof. FIG. 1 shows an example embodiment of a boat station 100 with an example embodiment of a seat 102 on an example embodiment of an independent suspension assembly 104 on an example embodiment of a seat base assembly 306 (see FIG. 3) that is in a lowered position. FIG. 2 shows the boat station 100 with the seat base assembly 306 in an upper position. FIG. 3 shows the seat base assembly 306 in the upper position and supporting a row of three seats 102, although any number of seats 102 may be supported by one seat shelf 300. The seat 102 optionally includes a bolster 110 and arm rests 112. The seat base assembly 306 is disposed within a seat base console 114. The seat base assembly 306 and the seat base console 114 may be composed of fiberglass, carbon fiber, aluminum, steel, or the like.

The independent suspension assembly 104 defaults to an independent suspension height 120 and the independent suspension height 120 is the same in FIG. 1 and FIG. 2. When the seat base assembly 306 is in the lower position of FIG. 1, there is first distance 122 between a reference point 124 on the seat base console 114 and a reference point 126 on the seat 102. When the seat base assembly 306 is in the upper position of FIG. 2, there is second distance 128 between the reference point 124 on the seat base console 114 and the reference point 126 on the seat 102. The seat base assembly 306 is configured such that the second distance 128 is greater than the first distance 122 by from six (6) inches to as much as twenty (20) inches or more.

In an example embodiment, the seat base assembly 306 includes a seat shelf 300 on which the seats 102 and independent suspension assemblies 104 are disposed. The seat base assembly 306 further includes one or more actuators 302 that adjust a height 304 of the seat shelf 300 above, for example, a deck 308 of the boat. In the example embodiment shown, there are two actuators 302, one at each end of the seat shelf 300. However, there may be one actuator (e.g., centered), or more than two actuators.

In an example embodiment, the actuators 302 include a telescoping assembly 320 secured to the seat shelf 300. The telescoping assembly 320 includes two or more telescope members 322, 324 longitudinally moveable relative to one another for moving the seat shelf 300 between the lower position and the upper position. The telescoping assembly 320 further includes a motive component 326 (such as a piston, a motor, or the like) to effect the longitudinal movement of the two or more telescope members 322, 324. The motive component 326 may be powered (e.g. electrical or hydraulic motors), may be manually assisted (e.g. gas shock(s), spring(s)), or may be manually operated (e.g. hand crank etc.). Other actuators known to the artisan may be used.

In an example embodiment, a first telescope member of the two or more telescope members 322, 324 is at least partially hollow such that the first telescope member defines

a channel. A second telescope member of the two or more telescope members 322, 324 may be at least partially disposed in the channel. The motive component 326 may be disposed within or adjacent the two or more telescope members 322, 324 and drive one telescope member relative to the other telescope member to create the telescoping action. Such a telescoping assembly is disclosed in U.S. patent application Ser. No. 16/540,770 published as US Publication number 2020/0055576, entitled "Telescoping Tower for a Boat", filed on Aug. 14, 2019, which is incorporated in its entirety herein.

In an example embodiment, one or more of the independent suspension assemblies 104 includes an independent suspension height adjustment mechanism 330 configured to adjust a height of the respective seat 102 relative to the seat shelf 300. The independent suspension height adjustment mechanism 330 may be incorporated into a shock/strut or may be a discrete mechanism. The independent suspension assembly 104 may include a rubber vinyl opaque boot 340 or a rubber vinyl translucent boot 342 (made of e.g., a transparent polyvinyl) to keep the mechanism clean etc.

FIG. 4 shows an example embodiment of the independent suspension assembly 104 that supports a respective seat 102. In this example embodiment, there are three suspension modules 400 interconnected via a connector member 402, but there may be one, two, or more than three suspension modules 400. Each suspension module 400 includes a suspension bottom member 404, a suspension top member 406 that supports the seat(s) 102, scissor mechanisms 408 connecting the suspension bottom member 404 to the suspension top member 406, and a spring/strut mechanism 410 connecting the suspension bottom member 404 to the suspension top member 406. Each spring/strut mechanism 410 includes a spring 412 (e.g., a coil spring) and optionally a damper 414. Although not shown in this example embodiment, the suspension module 400 may further include the independent suspension height adjustment mechanism 330. The suspension bottom member 404 and the suspension top member 406 may be composed of, for example, steel, aluminum, carbon fiber, or fiberglass.

When sufficient weight is applied to the suspension top member 406, free ends 420 of the scissor mechanisms 408 slide within slots 422 while fixed ends 424 remain fixed relative to their respective suspension member. This allows the suspension top member 406 to lower, thereby yielding to the applied weight. The spring 412 resists this yielding. The optional damper 414 dampens oscillations associated with the applied weight and the spring response. Alternately, or in addition to the independent suspension height adjustment mechanism 330, increasing the spring tension can increase the independent suspension height 120 while decreasing the spring tension can decrease the independent suspension height 120.

FIGS. 5 and 6 show an alternate example embodiment of a boat station 500. FIG. 5 shows an alternate example embodiment of a boat station 500 with an alternate example embodiment of the seat 502 on an example embodiment of an independent suspension 504 and an alternate example embodiment of the seat base assembly 506 (see FIG. 6) that is in the lowered position (e.g. flush with the seat base console 510). The independent suspension 504 can be any embodiment disclosed herein or any suitable independent suspension.

FIG. 6 shows the boat station 500 with the seat base assembly 506 in the upper position and protruding from the seat base assembly 506. The seat base assembly 506 is disposed within the seat base console 510. The operation of

this example embodiment of the seat base assembly 506 is similar to the operation described above for the seat base assembly 306 of FIG. 1. In at least the example embodiment of FIGS. 5-6, the seat base console 510 further includes a platform 512 that can be flipped up and locked in the upper position shown in FIG. 6. When in the upper position, the platform can function as a raised deck/floor for the captain.

FIGS. 7-9 show an example embodiment of an independent suspension. FIG. 7 shows an example embodiment of a seat 700 and an example embodiment of an independent suspension 702 with an example embodiment of an elastomeric element 704. The elastomeric element 704 may be composed of, for example, rubber (natural or synthetic), silicone, thermoplastic polyurethane (TPU), thermoplastic elastomers (TPE), and/or or polyurethane. FIG. 8 shows a closeup of the independent suspension 702 and FIG. 9 shows rear perspective view of the independent suspension 702.

The independent suspension 702 further includes a suspension bottom member 706 (e.g., a plate), a suspension top member 708 (e.g., a plate) to which the seat 700 is mounted, and a pivot joint 710 disposed toward a front 720 of the seat 700 and connecting the suspension top member 708 to the suspension bottom member 706. The suspension bottom member 706 and the suspension top member 708 may be composed of, for example, steel, aluminum, carbon fiber, or fiberglass.

The elastomeric element 704 and a coil spring 722 are disposed toward a rear 724 of the seat 700 and keep the suspension top member 708 from reaching the suspension bottom member 706 when an occupant is sitting on the seat 700. In this example embodiment, the coil spring 722 is nested inside the elastomeric element, although this is not necessary. In this example embodiment, the suspension bottom member 706 is secured to the seat shelf 726 of the seat base assembly 728. The elastomeric element 704 and the spring 722 together constitute a suspension component 730. There may be any number of suspension components 730 in one independent suspension 702.

As can be best seen in FIG. 8, the elastomeric element 704 comprises a plurality of elastomeric zig-zag columnar elements 800. The elastomeric zig-zag columnar elements 800 are optionally disposed parallel to a longitudinal axis 802 of the spring 722 and optionally in a spring volume 804 in the example embodiment of FIG. 8. The elastomeric zig-zag columnar elements 800 are shown separated from each other by an optional gap 806. One or more optional laterally extending elastomeric elements 808 span/connect two or more of the elastomeric zig-zag columnar elements 800.

The elastomeric zig-zag columnar elements 800 and/or the laterally extending elastomeric element 808 may include, in example embodiments, a thickness 810 from $1/16$ inch to $1/8$ inch, a width 812 of 2 inches to 10 inches and/or up to a width of a seat supported thereon, and a height 814 of $1/2$ inch to $2\frac{3}{8}$ inches. The elastomeric zig-zag columnar elements 800 include adjacent planar portions 820 oriented at an angle 822 to each other. Example angles include sixty (60) to one hundred twenty (120) degrees. In the example embodiment shown, the angle 822 is ninety (90) degrees. The thickness 810, the width 812, the height 814, and the angle 822 may be the same or they may vary throughout the elastomeric element 704. The elastomeric zig-zag columnar elements 800 may connect an elastomeric component bottom member 830 to an elastomeric component top member 832. The elastomeric component bottom member 830 and the elastomeric component top member 832 constitute at least part of a perimeter 834 of the elastomeric element 704, and the elastomeric zig-zag columnar elements 800 may

connect to any portion of the perimeter **834** and may span all or part of the way to another location on the perimeter **834**. The elastomeric zig-zag columnar elements **800** support the perimeter **834** to resist compression of the elastomeric element **704**.

The elastomeric zig-zag columnar elements **800**, the laterally extending elastomeric element **808**, the elastomeric component bottom member **830**, and/or the elastomeric component top member **832** may be composed of, for example, natural rubber (natural or synthetic), silicone, thermoplastic polyurethane (TPU), thermoplastic elastomers (TPE), and/or or polyurethane. In example embodiments, material that makes these components may be characterized by a shore hardness from 30A to 95A.

As can be seen in FIG. 10A, which shows the suspension components **730** alone, the suspension component **730** includes the elastomeric element **704** and the nested (coil) spring **722**. In this example embodiment, the spring **722** rests in and is held in position by a well **900** an opening **902** in the elastomeric component top member **832**. However, the opening **902** need not be present. In this example embodiment, there are two laterally extending elastomeric elements **808** that are disposed on opposite sides of the spring **722**.

FIG. 10B shows an alternate example embodiment of the elastomeric element **1000**. In this example embodiment, the elastomeric element **1000** does not have a spring volume to accommodate a nested spring **722**. As such, when the independent suspension uses this example embodiment of the elastomeric element **1000**, any spring **722** would be disposed outside of the elastomeric element **1000**. The elastomeric element **1000** includes the elastomeric zig-zag columnar elements **1002**, the optional gaps **1004**, and the optional laterally extending elastomeric elements **1006** that span/connect two or more of the elastomeric zig-zag columnar elements **1002**. However, adjacent elastomeric zig-zag columnar elements **1002** may be connected to each other via an interface **1008** and/or additional laterally extending elastomeric elements **1010** that span/connect two or more of the elastomeric zig-zag columnar elements **1002**. The elastomeric element **1000** may have a thinner elastomeric component bottom member **1020** and a thinner elastomeric component top member **1022** than the example embodiment of FIG. 8. The elastomeric element **1000** may otherwise be similar to the elastomeric element **704** described above including, but not limited to, the dimensions, materials, and other properties.

FIGS. 11 and 12 show an example embodiment of a seat **1100** disposed on the independent suspension **702** and the seat base assembly **728** of FIG. 7 with the seat shelf **726** in the lowered position. FIG. 13 and FIG. 14 show the seat **1100**, the independent suspension **702**, and the seat base assembly **728** with the seat shelf **726** in the raised position. Included in the seat base assembly **728** are the actuators **1102**, one at each end of the seat shelf **726**. In this example embodiment, the actuators **1102** include a telescoping assembly **1110** secured to the seat shelf **726**. The telescoping assembly **1110** includes two or more telescope members **1112**, **1114** longitudinally moveable relative to one another for moving the seat shelf **726** between the lower position and the upper position. The telescoping assembly **1110** further includes a motive component **1116** (such as a piston, a motor, or the like) to effect the longitudinal movement of the telescope members **1112**, **1114**. The motive component **1116** in this example embodiment is a threaded rod actuator, but any suitable actuator known to the artisan can be used.

In this example embodiment, a guideway **1120** in the telescoping member **1112** guides a block **1122** that moves with the telescoping member **1114**. The block **1122** is locked into in a guideway lower position **1124** when the seat shelf **726** is in the lower position, and a guideway upper position **1126** when the seat shelf **726** is in the upper position. The block **1122** may contact an upper position sensor **1128** when the seat shelf **726** is in the upper position to inform a controller of the location of the seat shelf **726** or to otherwise indicate the upward motion should stop.

In this example embodiment, a control feature **1130** is disposed within reach of a seated occupant and includes controls related at least to the operation of the seat base assembly **728**. The control feature **1130** includes at least one switch that can be used to raise and lower the height of the seat shelf **726**. In the example embodiment shown, the control feature **1130** extends from the seat shelf **726**.

FIG. 15 shows the seat **700**, the independent suspension **702**, and the seat base assembly **728** of FIG. 7 disposed in an example embodiment of the seat base console **1500**. The seat base assembly **728** is shown protruding from the seat base console **1500** to position the seat shelf **726** in the upper position. A weather seal **1502** may be disposed between the seat base assembly **728** (e.g., a side **1504** of the seat base assembly **728**) and the seat base console **1500** to form a seal to reduce or prevent water ingress.

FIG. 16 is a closeup of the weather seal **1502** showing a recess shaped and sized to receive and form a first seal with an edge **1510** of the seat base console, and a lip **1512** configured to abut and form a second seal with the side **1504** of the seat base assembly **728**. The lip **1512** is in sliding contact with the side **1504** of the seat base assembly **728** and maintains the sealing contact as the seat base assembly **728** moves up and down, thereby preventing water from passing between the weather seal **1502** and the seat base assembly **728**.

In addition, the weather seal **1502** includes a squeegee feature **1514** (e.g., a corner). When the seat base assembly **728** is lowered, friction between the side **1504** of the seat base assembly **728** and the lip **1512** drags the lip **1512** downward slightly. This draws the squeegee feature **1514** closer to the side **1504** of the seat base assembly **728** and causes the squeegee feature **1514** to act like a squeegee/wiper blade and wipe off any water disposed on the side **1504** of the seat base assembly **728**, thereby preventing water ingress into the seat base console **1500**. In this example embodiment the shape of the weather seal **1502** is asymmetric shape and therefore squeegee feature **1514** does not operate in the same manner when the seat base assembly **728** is raised. However, the shape may be symmetric such that two squeegee features are present, where one works when the seat base assembly **728** is raised and the other works when the seat base assembly **728** is lowered.

The weather seal **1502** also optionally includes a drain feature **1520** that is concave when unflexed and when friction from a raising/raised seat base assembly **728** raises the lip **1612**. When concave, the drain feature **1520** ramps water that is under the influence of gravity away from the side **1504** of the seat base assembly **728**. The weather seal **1502** is further configured so that when the lip **1512** and associated squeegee feature **1514** are dragged down slightly by the friction between it and the side **1504** of a lowering/lowered seat base assembly **728**, the drain feature **1520** either remains concave or flattens out without inverting into a convex shape. A flat drain feature **1520** will at least prevent squeegeed water from bunching up at the lip **1512**, and a concave drain feature **1520** even with reduced concavity will

still ramp water away. In light of the above, the apparatus disclosed represents an improvement in the art by providing a captain with a wide range of operating positions that are suitable for a wide range of operating conditions.

While various embodiments of the present invention have been shown and described herein, it will be obvious that such embodiments are provided by way of example only. Numerous variations, swapping of features among embodiments, changes, and substitutions may be made without departing from the invention herein. Accordingly, it is intended that the invention be limited only by the spirit and scope of the appended claims.

The invention claimed is:

1. A boat station, comprising:

a seat base assembly comprising a seat shelf, the seat base assembly configured to adjust a vertical position of the seat shelf;

at least two seats; and

an independent suspension assembly for each seat of the at least two seats, wherein each independent suspension assembly secures a respective seat to the seat shelf.

2. The boat station of claim 1, further comprising a seat base console in which the seat base assembly is at least partly disposed.

3. The boat station of claim 2, further comprising a weather seal disposed between the seat base assembly and the seat base console and comprising a squeegee feature configured to wipe water from the seat base assembly as the seat base assembly is lowered to prevent water ingress into the seat base console.

4. The boat station of claim 1, wherein the seat base assembly is configured to adjust the vertical position of the seat shelf by at least twenty (20) inches.

5. The boat station of claim 1, wherein the seat base assembly comprises an actuator disposed configured to adjust the vertical position of the seat shelf.

6. The boat station of claim 5, wherein the actuator is a powered actuator.

7. The boat station of claim 5, further comprising a second actuator configured to adjust the vertical position of the seat shelf, wherein the actuator is positioned at a first end of the seat shelf and the second actuator is positioned at a second end of the seat shelf.

8. The boat station of claim 6, further comprising a control feature disposed on the seat base assembly and configured to raise and lower the seat shelf based on operator input.

9. The boat station of claim 1, wherein each independent suspension assembly comprises a suspension top member, a coil spring, and an elastomeric element, wherein the coil spring and the elastomeric element are disposed between the suspension top member and the seat shelf.

10. The boat station of claim 9, wherein the independent suspension assembly further comprises a pivot joint secured to the suspension top member toward a front of the seat, and wherein the coil spring and the elastomeric element are positioned under a rear of the seat to counter downward motion of the seat.

11. The boat station of claim 9, wherein the coil spring is nested inside the elastomeric element.

12. A boat station, comprising:
a seat base console;
a seat base assembly disposed at least partly in the seat base console and comprising a seat shelf, the seat base assembly configured to adjust a vertical position of the seat shelf relative to the seat base console;
at least one seat; and
an independent suspension assembly for each seat of the at least one seat and configured to secure a respective seat of the at least one seat to the seat shelf.

13. The boat station of claim 12, the seat base assembly further comprising an actuator disposed in the seat base console and configured to adjust the vertical position of the seat shelf.

14. The boat station of claim 13, the actuator comprising a telescoping assembly.

15. The boat station of claim 12, wherein the at least one seat comprises at least two seats.

16. The boat station of claim 12, further comprising a weather seal disposed between the seat base assembly and the seat base console and comprising a squeegee feature configured to wipe water from the seat base assembly as the seat base assembly is lowered to prevent water ingress into the seat base console.

17. The boat station of claim 12, wherein the independent suspension assembly further comprises an elastomeric element and a pivot joint that is secured to a front of the seat, and wherein the elastomeric element is positioned under a rear of the seat to counter downward motion of the seat.

18. A boat station, comprising:
a seat base assembly comprising a seat shelf, the seat base assembly configured to adjust a vertical position of the seat shelf;
at least two seats disposed on the seat shelf; and
a seat base console in which the seat base assembly is at least partly disposed.

19. The boat station of claim 18, further comprising an actuator disposed in the seat base console and configured to adjust the vertical position of the seat shelf.

20. The boat station of claim 19, the actuator comprising a telescoping assembly.
